GASEOUS ELECTRIC DISCHARGE LAMP

Robert Rompe, Berlin, Germany, assignor to
General Electric Company, a corporation of
New York

Application June 14, 1935, Serial No. 26,674
Renewed November 16, 1938
In Germany June 25, 1934

4 Claims. (Cl. 176—42)

The present invention relates to gaseous electric discharge lamps generally.

The object of the invention is to provide a highly efficient gaseous electric discharge lamp emitting light which closely approximates daylight. Still further objects and advantages attaching to the device and to its use and operation will be apparent to those skilled in the art from the following particular description.

10 In accordance with this object the gaseous electric discharge lamp comprises a tubular quartz container having a starting gas therein, such as argon, krypton, xenon, or the like, and having an electrode at each end thereof consisting of tellurium. The discharge current in the lamp during the operation thereof is such that the container temperature is approximately 750° C. or more and the tellurium vapor is at a pressure of approximately 0.1 mm. or more. Such a lamp is 15 highly efficient and the spectrum of the light emitted thereby closely approximates that of daylight.

20 In the drawing accompanying and forming part of this specification a lamp embodying the invention is shown in a side elevational, partly sectional view.

25 Referring to the drawing the lamp comprises an elongated, tubular container 1 having an electrode chamber 2 at each end thereof. Said container 1 is sealed and consists of quartz. Each of said electrode chambers 2 has a quantity 30 of tellurium therein which is crystalline in structure when cool and which changes to a liquid when heated during the operation of the lamp.

35 A current lead 3 passes through the wall of the electrode chamber 2 and terminates in the tellurium 4. The joint between the current lead 3 and the wall of the electrode chamber 2 is a ground, gas tight, mechanical joint, well known 40 in the art, or, when desired, a step-seal consisting of a plurality of glass rings having coefficients of expansion intermediate that of quartz and the current lead 3 is used to join said leads 3 to said chambers 2. Said container 1 has a 45 fixed, starting gas therein, such as krypton, xenon or argon, or mixtures thereof.

50 The efficiency of the above described lamp increases as the current load, the container temperature and the vapor pressure therein increases. For example, when a discharge current of sufficient strength to heat the container 1 to a temperature of approximately 750° C. and to raise the tellurium vapor to a pressure of about 0.1 mm. is used the lamp has an efficiency of 55 about 24 lumens per watt. When the current

strength is increased to the point that the container temperature is 1000° C. and the tellurium vapor pressure is about 1 mm. the lamp has an efficiency of about 40 lumens per watt. When the current strength is such that the container temperature is 1100° C. and the tellurium vapor pressure is about 10 mm. the efficiency of the lamp is about 60 lumens per watt. This last example represents about the upper limit of efficiency of the lamp since at higher temperatures 10 gases diffuse through the walls of the quartz container. The container temperature should be greater than 750° C. however since the light emitted by the lamp is bluish or true blue in color below this container temperature. 15

The above described lamp is also useful in therapeutic work since it emits ultra-violet rays of long wave length. When desired, fluorescent materials are used with the lamp to transform the ultra-violet light into visible light to supplement the visible light emitted by the lamp. When desired the lamp is provided with a heat conservator to reduce the heat losses therefrom to a minimum and to improve the efficiency of 20 the lamp. 25

While I have shown and described and have pointed out in the annexed claims certain novel features of the invention, it will be understood that various omissions, substitutions and changes in the forms and details of the device illustrated 30 and in its use and operation may be made by those skilled in the art without departing from the broad spirit and scope of the invention.

What I claim as new and desire to secure by Letters Patent of the United States, is: 35

1. An electric discharge lamp comprising an elongated, sealed container of material transparent to light rays, an electrode chamber at each end thereof, a quantity of luminosity producing, vaporizable tellurium in each of said electrode 40 chambers, a current lead terminating in the tellurium in each of said electrode chambers and a fixed, starting gas in said container, said current leads being capable of conducting sufficient electrical energy to said lamp to maintain a tellurium 45 vapor pressure therein greater than 0.1 mm.

2. An electric discharge lamp comprising an elongated, sealed container of material transparent to light rays, an electrode chamber at each end thereof, a quantity of luminosity producing, vaporizable tellurium in each of said electrode 50 chambers, a current lead terminating in the tellurium in each of said electrode chambers and a fixed, starting gas in said container, said current leads being capable of conducting suffi- 55

- cient electrical energy to said lamp to maintain the container at a temperature of more than about 750° C. and to raise the tellurium vapor to a pressure giving a luminous efficiency of more than about 24 lumens per watt.
3. An electric discharge lamp comprising an elongated, sealed container of material transparent to light rays, an electrode chamber at each end thereof, a quantity of luminosity producing, vaporizable tellurium in each of said electrode chambers, a current lead terminating in the tellurium in each of said electrode chambers and a fixed, starting gas in said container, said current leads being capable of conducting sufficient electrical energy to said lamp to maintain the container at a temperature of between about

750° C.-1100° C. and to raise the tellurium vapor to a pressure giving a luminous efficiency of between about 24 to 60 lumens per watt.

4. An electric discharge lamp comprising a sealed container of material transparent to light rays, electrode leading-in wires sealed through the wall of said container and spaced apart therein, a charge of rare gas in said container and a quantity of tellurium metal in said container, said lamp being constructed to operate with an electric discharge at a temperature at which the tellurium vapor in the path of said discharge has a sufficiently high density to cause the characteristic spectrum of said vapor to predominate in the light emitted by said lamp.

ROBERT ROMPE.
